Filed Mar. 20, 1968, Ser. No. 11,060

Term of patent 14 years

U.S. Cl. D34—5

Int. Cl. D21—04

FIG. 1

FIG. 2

FIG. 3

FIG. 1 is a side elevational view of a playground climber with a moon face in accord with my new design, the opposite side being identical thereto,

FIG. 2 is a top plan view of a playground climber in accord with my design, and

FIG. 3 is an end elevational view, the opposite end view being identical thereto.

The characteristic feature of my design resides in the downwardly projecting moon face portions located on each of the outer, large diameter arches of the arch-shaped climber.

I claim:

The ornamental design for a playground climber with moon face, substantially as shown and described.
